UNITED STATES PATENT OFFICE.

GERRIT MARIE ELIZE POS, OF AMSTERDAM, NETHERLANDS.

DEVICE FOR THE PRODUCTION OF FIBERS FROM PLANTS.

1,089,261.

Specification of Letters Patent.

Patented Mar. 3, 1914.

Application filed August 5, 1912. Serial No. 713,451.

To all whom it may concern:

Be it known that I, GERRIT MARIE ELIZE Pos, a subject of the Queen of the Netherlands, residing at Amsterdam, Netherlands, have invented certain new and useful Improvements in Devices for the Production of Fibers from Plants, of which the following is a specification.

The present invention relates to apparatus for obtaining fibers directly suitable for spinning, from fresh stalks supplying green fibers, such as ramie, jute hemp and the like, as well as from leaves.

Generally speaking, the fresh green stalks to be treated according to this invention are first deprived of their peel. The sap or juice is then expressed from the latter, which is at the same time washed, for the purpose of removing vegetable gum, resinous ingredients, etc. After the drying, which can be effected for instance by means of hot air or the like, the fibers are deprived mechanically, in a special manner, in the final operation, from further impurities such as dust, reedy portions, etc.

If the fibrous material is to be obtained from leaves and similar parts of plants, the latter, of course, do not require any previous removal of peel. It is, however, advisable to first cut them into narrow strips in the direction of the fibers. For the rest, the various stages of treatment can be suitably modified according to the nature of the material to be treated.

An embodiment of the invention is illustrated in the accompanying drawings in which—

Figure 1 is a longitudinal section through the machine; Fig. 2 is, on the left hand half, a section on the line I—II, and on the right hand half, a section on the line III—IV of Fig. 1; Fig. 3 is a section through the essential part of Fig. 1 on a larger scale; Fig. 4 is a plan of a stalk as it is being gradually split; Figs. 5, 6, and 7 are sections through the stalk on the lines V—VI, VII—VIII and IX—X, respectively, Fig. 4; Fig. 8 is a diagrammatic view of the devices in which the stalks are consecutively treated; Fig. 9 is a cross-section through that part of the device in which the bark, removed from the core, compressed and washed, is deprived of further impurities; and Fig. 10 is a longitudinal section on the line XI—XII of Fig. 1.

The first treatment to which the fresh

green stalks are submitted consists in the peel being stripped off from the core, which is effected by means of the apparatus shown in Figs. 1 to 3. The shaft 1 is carried by a frame 2, and may be driven in any suitable manner, for instance by the belt 3, the drum 5 being driven from said shaft by means of a chain and sprocket connection 4. A belt 6 of the full breadth of the drum 5 and placed in an inclined direction drives the drum 7, so that the belt forms a conveyer or feeder. Two rubber rollers 8 and 9 are arranged in such a manner in the frame 2 that while the rollers are arranged one above the other, the upper roller 8 can be pressed upon the roller 9 by means of hand screws 10 which are connected to each other by chain gearing, and which act upon a spring 11 in the known way. The shafts of these rollers are preferably provided on both sides with gears 12 and 13 meshing with each other. The shaft of the roller 9 is preferably provided on each side with two sprockets 14 connected to the shaft 1 by means of a chain, so as to rotate in the direction indicated by the arrows in Figs. 1 and 3. The roller 9 may, however, be driven in any other suitable manner. A knife blade 15 is connected to sliding blocks 16 mounted in guides 17 in the frame, the blade being disposed either perpendicularly or in a slanting direction. The screws 18 threaded into the sliding blocks 16 protrude through openings in the frame and carry nuts 19 on their upper ends, springs 20 being arranged around said screws and resting on the sliding block 16, so as to tend to keep the knife in the lowest position the nuts 19 allow. The knife is resilient, and its lowest position can be determined by means of the screws 18 and nuts 19. At the opposite side of the rollers 8 and 9, a table 21 is rigidly connected to the frame and a cover 22 is arranged above this table. Beneath the outer end of the table 21 are placed two rollers 23 and 24, which correspond in length with the width of the frame, a curved plate 25 being arranged above the roller 24 and flush with the table. Under the said table is also arranged a drum 26 which is rotated by means of the rollers 27, 28 and 24 and the broad belt 29, the roller 27 being connected by gearing to shaft 1.

The operation is as follows:—The stalks 30 are laid upon the inclined belt 6, their tops being directed toward the roller 9, so that they would, therefore, proceed in a

straight line from the belt 6 to the roller 9 if they were entirely stiff and hard. The said tops, however, are flexible and for this reason they bend slightly downward with the belt 6 on the drum 7, but as soon as they touch the roller 9 they are conveyed upward again and are brought between the rollers 8 and 9 where they are completely flattened, as the core and other parts, except the bark, 10 are weak and juicy at the top of the stalks. Now the rollers 8 and 9 are rotated at such a speed that the stalk is drawn along at a greater speed than the belt 6, so that the flexible top of the stalk which had bent 15 downward on reaching the drum 7 is raised as soon as it contacts with roller 9 and pulled forward between the said rollers 9 and 8. This pulling forward of the stalk has the effect of lifting it a slight distance above the 20 end of the belt until it touches the edge of the spring-pressed blade 15 which causes it to form a slight angle. The skin on the convex side of the stalk angle is thereby stretched, but slackens on the concave side. 25 On advancing, the slackened part of the skin is drawn across the knife blade and is thereby scraped or wounded, so that the tension of the peel at the other side of the stalk causes it to burst open along the scraped 30 line, while the pressure of the rollers 8 and 9 causes the weak core to burst open along the same line as the skin. In this manner, the top of the stalk is laid entirely open. As the stalks proceed through the rollers 8 and 35 9, the cores become gradually harder and stiffer so that they tend to form a straight line from the belt 6 to the rollers 8 and 9. The resilient knife 15 is now adjusted to 40 bend the stalks just a little downward. The tension of the stalks will then be sufficient to cause the knife to scrape and wound the stalks on their uppermost side as they proceed under this knife. As the wounded stalks, which grow thicker toward the end, 45 proceed between the rollers 8 and 9, the peel 31 will burst open along the wounded line (Fig. 4) and will be laid open in the form of a flat ribbon 32 which is neither split nor torn. (Figs. 4 and 7). The core 33 will 50 also split open over the same line, as shown in section in Fig. 6, and will be gradually laid open also, as shown in Figs. 4 and 7. The two core halves will be crushed between the rollers 8 and 9 and the stalk will show 55 the section illustrated in Fig. 7, after having passed the rollers.

From the rollers 8 and 9, the stalks, flattened in the described manner, proceed over the table 21. The flexible tops of the flattened stalks are thereby pushed along, fall 60 downward over the edge 34 of the table 21, and are grasped between the rollers 23 and 24, which rollers draw them down and bring them between the belt 29 and the drum 26. 65 The crushed weak core of the top end of the

stalk will also bend downward, but as the core grows harder and stiffer and is loosened from the bark by the pressure of the rollers, it will no longer bend downward but will break off and proceed over the curved plate 70 25, thus effecting the stripping of the bark from the cores.

The bark is clenched between the belt 29 and the drum 26, and is transported by said belt to the roller 27 and out of the machine, 75 while the cores proceed over the curved plate 25 and fall directly out of the machine, the cover 22 preventing the ends of the cores from being lifted when they pass beyond the rollers 8 and 9. By that process, peel is 80 obtained in the shape of undamaged bands which, however, still contain sap, etc. For the purpose of removing these ingredients from the bands, the latter are pressed so that all the sap is forced out of them, this being 85 done by means of rolls in the following manner: The green bark is passed between two metal rolls or rollers 35, 36, (Fig. 8), forcibly pressed against each other, the roll 36 being driven by means of a third roll 37 which is firmly pressed against it, said roll 37 also contacting with and driving the rolls 38 and 39. In order that all the rolls should rotate in the direction indicated by the arrows, it is necessary to drive only the 90 roll 37. The bark is then pressed out first between the rolls 35 and 36, then between the rolls 36 and 37, and finally between the rolls 37 and 38 and 38 and 39. These rolls, which are preferably made of copper, squeeze out 100 all the cells of the peel in a thorough manner, and the jets of water 40, 41 and 42 directed between and against the rolls, wash away all the sap expressed, together with the resinous portions of the same. The immediate removal of these resinous portions is indispensable as if they are given time to harden or to thicken in the air, their removal becomes difficult. Any hard portions of the core which still adhere to the peel are split 110 and removed by the said rolls. After the peel has been thus passed between the rolls, the fibers, which are then practically dry, are first completely dried by hot air or the like, and then submitted to a further treatment consisting in the removal of the dust and scale still contained in them. This final treatment is effected by brushing the fibers by means of the device hereinafter described.

In a frame 43 is arranged a drum 44 secured to a shaft 45, the cylindrical casing of which drum is constituted by a large number of parallel slats 46 arranged longitudinally and spaced a slight distance apart from each other. Around this drum are 125 mounted in the said frame 43 a number of cylindrical brushes 47, all of which rotate in the direction indicated by the arrows, Fig. 9, and there are also mounted in the frame two rubber rolls 48 and 49 which 130

press against each other with moderate force. The shaft of the roll 49 is preferably driven by a peripheral flange 50 on the drum 44, either directly or through the agency of a suitable gear, and as the said flange 50 is broken at two points 51 and 52, the rolls 48 and 49 are stopped during given periods of time. Over the drum 44 and the sprockets 53, 54, 55, 56 and 57 are led two chains 58 between which are mounted bars 59 arranged at distances apart equal to half the circumference of the drum, these bars being of circular cross-section and being adapted to periodically engage with the corresponding grooves 60 in the drum surface. The said bars are firmly pressed against that portion of the drum circumference over which the chains pass, owing to the provision of rolls 61 on the bars which engage with the inner edges of the rings 62 secured to the frame concentrically with the drum. Over the rolls 63 and 64 secured to the shafts of the sprockets 55 and 56, passes an endless slatted belt 65, and between this belt and the drum is arranged a circular brush 66 which is adapted to brush the fibers on the belt. Adjacent the rolls 48 and 49 is arranged a small flap 67, for a purpose hereinafter described, while finally the feed belt 68 supplies the fibers to be treated. The working of this part of the machine is as follows: The fibers coming from the rolls 38 and 39, Fig. 8, and still containing broken and split portions of the core, etc., are delivered in a dry state by the belt 68, with their points directed forward. They are seized by the rubber rolls 48 and 49, drawn therebetween, and fed over the flap 67 to the slatted belt 65. The points or ends of the fibers are brushed completely clean on the same belt 65 by the brush 66, which latter rotates in the direction indicated by the arrow, as the brush not only attacks the surface of the fibers, but also passes partly through the fibers at the spaces between the slats. The dust and the like will, therefore, be brushed out of the fibers between the slats, and will then fall down to the bottom of the machine. When a certain portion of the fiber points is stretched out on the slatted belt, the gap 51 in the vertical flange 50 of the drum comes opposite the shaft of the roll 49, so that the latter will be no longer driven. The bar 59 then passes between the rolls 48 and 49 and the brush 66, raises the flap 67 and pulls back the fibers from under the brush 66, the rolls 48 and 49 holding the fibers. The flap 67 then returns to its original position, while the bar 59 lifts the fiber points completely brushed by the brush 66, and forces them into the cylinder casing, as the rolls 61 of the bars 59 engage with the rings 62. The fibers are then carried around with the drum, and therefore pass

from the feed belt 68 around the roll 49, and are then deposited on the drum slats where they are brushed by the brushes 47, in the same way as on the belt 65. The dust, woody portions, etc., are again driven in between the slats of the drum, as the brushes again penetrate between the fibers and therefore clean them completely. Purified fibers directly suitable for spinning can therefore be removed on the left hand side of Fig. 8 from the machine. The next layer of fibers supplied, is treated in exactly the same manner. Instead of using a slatted drum, a drum with a corrugated surface might be used, in which case the action would remain approximately the same.

The number of brushes can be modified if required, and one or more leather brushes may be arranged on the circumference of the drum for treating the fibers. These leather brushes are made of a number of leather plates secured to a shaft rotating at a fairly high speed and beating the fibers clean.

What I claim as my invention and desire to secure by Letters Patent is:—

1. In a machine for the production of fibers from plants, the combination of a downwardly-inclined conveyer for feeding the stalk of the plant, flexible end first; a pair of superposed co-acting flattening rollers located adjacent the delivery end of said conveyer; and a spring-pressed knife located between said rollers and said conveyer end, said rollers having a greater surface speed than said conveyer for raising the stalk above the latter, as it leaves the same, into contact with the edge of said knife, whereby the under surface of the stalk is stretched and the upper surface thereof scored longitudinally and the peel and core are caused to split along the line of scoring by the tension of the said stretched surface, the split peel and core being flattened during their passage between said rollers.

110

2. In a machine for the production of fibers from plants, the combination of a downwardly-inclined conveyer for feeding the stalk of the plant, flexible end first; a pair of superposed co-acting flattening rollers located adjacent the delivery end of said conveyer, a spring-pressed knife located between said rollers and said conveyer end, said rollers having a greater surface speed than said conveyer for raising the stalk above the latter, as it leaves the same, into contact with the edge of said knife, whereby the under surface of the stalk is stretched and the upper surface thereof scored longitudinally and the peel and core are caused to split along the line of scoring by the tension of the said stretched surface, the split peel and core being flattened during their passage between said rollers; a table for receiving the flattened peel and core

125

130

from said rollers; and a pair of coacting rollers below the end of said table for seizing and pulling downward the front end of the peel when said end drops over the table end to separate the peel from the stiffer core.

3. In a machine for the production of fibers from plants, the combination of a downwardly-inclined conveyer for feeding the stalk of the plant, flexible end first; a 10 pair of superposed coacting flattening rollers located adjacent the delivery end of said conveyer, a spring-pressed knife located between said rollers and said conveyer end, said rollers having a greater surface speed 15 than said conveyer for raising the stalk above the latter, as it leaves the same; into contact with the edge of said knife, whereby the under surface of the stalk is stretched and the upper surface thereof scored longitudinally and the peel and core are caused to split along the line of scoring by the tension of the said stretched surface, the split peel and core being flattened during their passage between said rollers; a table for receiving the flattened peel and core from said 20 rollers; a pair of coacting rollers below the end of said table for seizing and pulling downward the front end of the peel when

said end drops over the table end to separate the peel from the stiffer core; a series of 30 rollers for seizing the separated peel and expressing the sap therefrom; and means for washing said peel with a sap-dissolving liquid during the expressing operation.

4. A device for cleaning vegetable fibers 35 comprising in combination a pair of rubber rolls in contact adapted to feed the fibers, an endless belt composed of slats arranged in spaced parallel relation adapted to receive the fibers, a small pivoted flap between 40 said rolls and said belt, a rotating brush situated above the belt and adapted to brush and clean the ends of the fibers, a drum consisting of spaced parallel strips to which the cleaned ends of the fibers are secured, 45 and rotating brushes around said drum adapted to clean the fibers throughout their length.

In testimony whereof I have signed my name to this specification in the presence of 50 two subscribing witnesses.

GERRIT MARIE ELIZE POS.
